UNITED STATES PATENT OFFICE.

JOHANN STUMPF, OF BERLIN, GERMANY.

REGULATING DEVICE FOR STEAM-TURBINES.

SPECIFICATION forming part of Letters Patent No. 728,041, dated May 12, 1903.

Application filed December 26, 1901. Serial No. 87,280. (No model.)

To all whom it may concern:

Be it known that I, JOHANN STUMPF, a subject of the King of Prussia, German Emperor, and a resident of 27 Rankestrasse, Berlin, 5 Kingdom of Prussia, German Empire, have invented a new and Improved Regulating Device for Steam-Turbines, of which the following is an exact specification.

My invention relates to a regulating device 10 for steam-turbines; and it consists of means for throttling the admission-steam in case the turbine runs too quickly.

My invention is represented in the accompanying drawings, in which—

15 Figure 1 is a vertical section of part of the turbine-casing provided with the regulating device. Fig. 2 is a modification of the regulating device shown in Fig. 1. Fig. 3 shows this modification in another position. Figs. 20 4, 5, and 6 show further modifications of the device.

The steam is led to the turbine-wheel proper by means of a plurality of nozzles *b*, separated one from the other by means of partitions *a*. In the construction shown in Fig. 1 several nozzles are united, so as to form groups I, II, and III. The groups II and III are connected to an annular channel *d*, situated around the whole turbine-wheel, by means of 25 openings *i*. The annular channel *d* is connected with the steam-admission pipe *g*, so that in this channel the steam has the same tension as the steam in the boiler. Around the annular channel *d* a second annular channel *e* is situated. In the partition *c*, separating the channel *d* from the channel *e*, bores are provided, in which valve-pistons *k* are situated. These valve-pistons *k* are adapted to close the holes *i*. For this purpose spiral 30 springs *l* are provided, which are situated between the pistons *k* and screws *l'*, closing the holes in the outer turbine-case, which holes serve for putting in the valves *k*, and which springs press the pistons *k* down upon the 35 openings *i*. The annular channel *e* is connected to the steam-admission pipe *g* by means of a pipe *h*. Within this pipe *h* a throttling-valve *m* is provided, which is adjusted by means of a governor *R*. One or 40 several admission-nozzles *b* (in the drawings group I) are directly connected with the annular channel *e*. The nozzles of the group 45

I receive in consequence hereof steam entering through the channel *e* and the pipe *h*. The number and the diameter of these nozzles are advantageously so that the steam entering through the same is sufficient to drive the turbine-wheel in case the turbine is not loaded at all. The arrangement of these nozzles has the purpose that the steam can always 55 stream off the channel *e*, which is necessary in order to attain an exact effect of the device.

The effect of the device is as follows: The throttling-valve *m*, situated in the pipe *h*, is 60 constructed so as to be opened in case the turbine runs too quickly and to be closed in case the revolutions of the same are diminished. When the turbine does not run, the valve *m* will therefore be closed, while in case 65 of high revolutions it will be opened. When the turbine shall be started, all the valves *k*, as well as the throttling-valve *m*, will be closed. As soon as steam is led in through the pipe 70 *g* this steam will enter the annular channel *d*, while in the channel *e*, in consequence of the valve *m* being closed, nearly no steam at all will be contained. By the effect of the steam in the channel *d* the valves *k* will be 75 opened against the effect of the spiral springs *l*, so that the steam can enter through the openings *i* and stream through the nozzles *b* to the turbine-wheel, which in consequence 80 hereof begins to rotate. As soon as the required number of revolutions is attained the 85 governor begins its activity, consisting in more or less opening the throttling-valve *m*. By opening this valve *m* the pressure in the annular channel *e* increases, so that the spiral springs *l* will come in activity and will 90 more or less close the valves *k*, thereby reducing the quantity of steam streaming through the nozzles *b* and reducing in consequence 95 thereof the number of revolutions. In case now the number of revolutions gets too low the throttle-valve *m* is closed again by the 100 governor. In consequence thereof the pressure in the channel *e* is reduced and the valves *k* are opened more and more, so that more steam can stream to the openings *i*. It will be understood that by choosing spiral springs *l* with different tensions or different forms of valve-pistons *k* the arrangement can be such as to effect that all the valves *k* do not come

in activity in the same moment, but that the several groups of nozzles get steam one after the other. In case the turbine runs without being loaded at all the governor R opens the 5 valve *m* perfectly, so that in the channel *e* the same pressure is contained as in the channel *d* and all the valves *k* will be closed by the effect of the spiral springs *l*, the steam only streaming upon the turbine-wheel through 10 the nozzles of the group I. This steam, as mentioned above, is sufficient for rotating the turbine-wheel in this case.

The construction shown in Figs. 2 and 3 differs from the construction shown in Fig. 1 15 by the openings between the channel *d* and the groups of nozzles not being opened at once as soon as the steam is led in, but being opened gradually. For this purpose small cylinders *n* are arranged in the partition between 20 the channel *d* and the chambers *f*. These cylinders are connected with the chambers *f* by the channels *o*. Within the cylinders *n* pistons *p* are provided, which pistons are connected by means of a connecting-rod 25 *q* with pistons *r*, situated in a cylindrical bore *s*, provided in the partition separating the channels *d* and *e*. The pistons *r* are solid, while the pistons *p* are provided with holes or slots running parallel to the curved sides 30 of the same. The spring *l* in this construction is situated between the screw *l'* and the piston *r*. In order to attain a better effect, the piston may be provided with differential surfaces. In its lowest position, Fig. 2, the 35 piston *p* closes the channels *o*. Now in case the pressure in the channel *d* is so much greater than the pressure in the channel *e* that the piston *r* is moved against the tension of the spring *l* and against the pressure in the 40 channel *e* the piston *p* will open the channels *o*, as may be seen from Fig. 3. This opening naturally takes place gradually and not suddenly, as in the construction shown in Fig. 1.

Instead of arranging groups of nozzles, for 45 each of which groups one or several valves are provided, a special valve may be provided for each nozzle—as shown, for instance, in the vertical cross-section shown in Fig. 4. In this construction the nozzles *b* are situated 50 partly within the annular channel *d*, connected to the steam-admission pipe *g*. The arrangement of the annular channel *e* and the connection of the same to the admission-pipe *g* by means of the pipe *h*, as well as the arrangement of the governor and the throttling- 55 valve, may be the same as in the construction described above. Each nozzle *b* is closed by means of a valve *k*. This valve *k* is connected by means of a connecting-rod *q* with a piston 60 *r*, moving in a cylindrical bore of the turbine-casing. A spiral spring *l* is provided in the same way as described above, which tends to close the valve *k*. The spaces *u* above the pistons *r* are connected by the passages *v* 65 with the annular channel *e*. The effect of this modification is the same as that of the construction first described. In case the pres-

sure in the channel *d* is higher than the pressure within the channel *e*, together with the tension of the springs *l*, the valves *k* will be 70 opened. In case the steam-pressure in the channel *e* and the springs *l* together have more power than the steam-pressure in the channel *d* the valves *k* will be closed, so that no more steam can enter the nozzles *b*. 75

In the construction shown in Fig. 5 the valve *k* is connected by means of the connecting-rod *q* to the piston *r*, which is situated in a cylindrical bore of the turbine-casing. *y* is a packing for preventing the steam 80 contained in the channel *d* from entering into the cylindrical bore. The space *t'* above the piston *r* is connected by the channel *t''* with the annular channel *d*. The annular channel *e* is in the same way as in the construction 85 as shown in Fig. 4 connected with each cylindrical bore for one of the pistons *r* by means of the passages *v*. The space beneath the piston *r* is called *t''* in the drawing. In this construction the steam contained in the 90 annular channel *d* and entering the space *t'* through the channel *t''* tends to close the valve *k*. The opening of the valve is effected by means of the spiral spring *l* and the steam contained in the annular channel *e*, the pressure of which steam is regulated by means of a governor and a throttle-valve in the same way as in the construction shown in Fig. 1. The governor in this construction must be connected with the throttling-valve 100 in that way that in case the revolutions increase the throttling-valve is closed, so that in the space *t''*—that is to say, beneath the piston *r*—the steam-pressure is diminished. In starting the turbine the throttling-valve 105 consequently will be open and the same pressure will be on both sides of the pistons *r*, the opening of the valves *k* being effected only by the spiral springs *l*. In case the revolutions of the turbine are too high the throttling-valve will be closed by the governor, 110 and the steam-pressure in the annular channel *e* and in the space *t''* underneath the piston *r* will be diminished, so that the valves will be closed by the overpressure in the 115 space *t'*.

In Fig. 6 of the drawings another modification is shown, in which modification the spiral springs *l* are done away with. The opening and closing of the valves *k* is in this construction effected only by the difference of the pressure on both sides of the pistons. The valve *k*, which may be destined for a single nozzle *b* or for a group of nozzles, is connected by means of the connecting-rod *q* 120 with the piston *r*. This piston is situated in a steam-cylinder closed on both sides. The spaces *u'* above the pistons are connected with an annular channel *w* by means of passages *v*. The spaces *u* underneath the pistons are connected with an annular channel *w'* by means of passages *v'*. Both annular channels *w* and *w'* are connected with a governor. In the channel *d* is the full steam- 125 130

pressure. In this construction the valves *k* will never adopt a throttling position, but will either be perfectly closed or perfectly opened. It will be understood that also in 5 this construction spiral springs may be provided above or underneath the pistons *r*, which spiral springs have the purpose of attaining that not all the valves are opened or closed simultaneously but one after the 10 other.

Having thus fully described the nature of this invention, what I desire to secure by Letters Patent of the United States is—

1. In a regulating device for steam and gas turbines, the combination of the steam-admission nozzles *b* with valves *k* for closing these nozzles, a channel *d* directly connected to the steam-admission pipe *g*, said channel being connected to the nozzles by means of 15 the valves *k* mentioned above, a second channel *e* connected to some of the nozzles *b* and to the pistons of the valves *k*, said channel being connected to the steam-admission pipe *g* by means of a passage *h* and throttling 20 means situated in this passage, substantially as described and for the purpose set forth.

2. In a regulating device for steam and gas turbines, the combination of the steam-admission nozzles *b* with valves *k* for closing 25 these nozzles, a channel *d* directly connected to the steam-admission pipe *g*, said channel being connected to the nozzles by means of the valves *k* mentioned above, a second channel *e* connected to some of the nozzles *b* and 30 to the pistons of the valves *k*, said channel being connected to the steam-admission pipe *g* by means of a passage *h*, throttling means 35 situated in this passage and means for operating the same, substantially as described and for the purpose set forth.

ating the same, substantially as described and for the purpose set forth.

3. In a regulating device for steam and gas turbines, the combination of the steam-admission nozzles *b* with valves *k* for closing these nozzles, a channel *d* directly connected to the steam-admission pipe *g*, said channel 40 being connected to the nozzles by means of the valves *k* mentioned above, a second channel *e* connected to some of the nozzles *b* and to the pistons of the valves *k*, said channel being connected to the steam-admission pipe 45 *g* by means of a passage *h*, throttling means situated in this passage and a governor for operating the same, substantially as described and for the purpose set forth.

4. In a regulating device for steam and gas turbines, the combination of the steam-admission nozzles *b* with valves *k* for closing these nozzles, a channel *d* directly connected to the steam-admission pipe *g*, said channel being connected to the nozzles by means of 50 the valves *k* mentioned above, a second channel *e* connected to some of the nozzles *b* and to the pistons of the valves *k*, said channel being connected to the steam-admission pipe *g* by means of a passage *h*, throttling means 55 situated in this passage, a governor for operating the same and means for opening and closing the valves *k*, substantially as described and for the purpose set forth.

In testimony whereof I have signed my 60 name to this specification in the presence of two subscribing witnesses.

JOHANN STUMPF.
